UNITED STATES PATENT OFFICE.

JOHN B. NAU, OF NEW YORK, N. Y.

ASH REMOVING AND POKING APPARATUS FOR GAS-PRODUCERS.

1,161,404.

Specification of Letters Patent.

Patented Nov. 23, 1915.

Application filed February 23, 1912, Serial No. 680,408. Renewed April 22, 1915. Serial No. 23,218.

To all whom it may concern:

Be it known that I, JOHN B. NAU, a citizen of the United States, and a resident of New York city, in the county of New York and State of New York, have invented certain new and useful Improvements in Ash Removing and Poking Apparatus for Gas-
Producers, of which the following is a specification.

10 This producer belongs to the class known as suction or downdraft producers in which the supply of air for supporting combustion is received at the top of the producer chamber and conducted downwardly through the
15 fuel. The suction that will induce the air to enter the producer is obtained either by a gas engine run with the gas from the producer, an exhaust fan or any other suitable means. As the location of the suction means
20 is immaterial, they are not shown on the drawing.

The special aim of the producer is to gasify bituminous coal, known to contain a high percentage of volatile matter, such as
25 heavy hydrocarbons, which, owing to their easy decomposition at high temperatures into lighter hydrocarbons with deposit of free carbon, cannot well be used in their original state for power purposes. It is necessary to first transform them into fixed
30 gases such as carbon monoxid and hydrogen, practically free from tar, by running them through a bed of incandescent coke in presence of the oxidizing elements air and steam,
35 before they leave the producer.

The treatment of bituminous coal in a down-draft gas producer can best be obtained by providing in the upper region of the latter a distillation chamber into which
40 the raw coal is charged, there to be submitted to an energetic distillation, whereby the heavy unstable hydrocarbons are driven out, enter lower down a field of incandescent coke, derived from the distilled coal
45 descending from the distillation chamber, and come further into intimate contact with hot air and steam, whereby the desired transformation into permanent gas is effected. However, ordinary downdraft gas producers
50 present two defects: 1. The coal in the distillation chamber when descending, has a tendency to stick to the nozzle of the twyer, thereby giving rise to serious disturbances;
2. In the combustion chamber, especially in
55 its lower region, owing to coal and gas al-

ways going in the same downward direction, the forming ashes and clinkers have a tendency to pack sometimes to such an extent as to render the passage of gas impossible.

One of the purposes of the herewithin proposed producer is to obviate the above two defects.

In the drawings, Figure I. is a vertical cross-section on line I—I of Fig. III; Fig. II. is a vertical cross-section left incomplete on top, on line II—II of Fig. IV., Fig. III. is a top plan view, showing the mechanical operating means only in diagram, and a central part cut on line III—III of Fig. I., Fig. IV. is a horizontal cross-section on line IV—IV of Fig. II., Fig. V. is a vertical cross-section of the twyer; Fig. VI. a horizontal cross-section on line VI—VI of Fig. V.; Fig. VII. a horizontal cross-section on line VII—VII. of Fig. V.; Fig. VIII. a horizontal cross-section on line VIII—VIII of Fig. V. and Fig. IX. a top plan view of the lifting cross-piece of the drum.

In the drawings 1 represents a metallic shell inclosing the upper part of the producer, 2 a metallic shell inclosing the lower part or ash pit, 3 a combustion or gas producing chamber inclosed in fire brick lining 4, 5 a metallic hopper separating the distillation chamber 6 from the surrounding hot air chamber 7. A top plate 8 covers the producer, the distillation chamber 6 and hot air chamber 7. On top plate 8 are placed coal hoppers 9 to charge coal into chamber 6. A centrally located twyer 10, normally closed on top by cover 11, extends downwardly into the producer and is keyed or otherwise fastened on its top part to a spur gear 12, which in its turn is bolted to a circular disk 13 provided with an annular downwardly extending flange 14, reaching into a lower trough 15, making part of a circular box 16, placed on top of plate 8 and loosely surrounding twyer 10. The lower face of the outer rim of disk 13 and the upper face of the top flange of box 16 have corresponding grooves, between which are placed friction balls 17. Air inlet 18 and continuing air duct 19 establish communication between box 16 and air chamber 7. Trough 15 can receive liquid or sand or other similar material to maintain an airtight loose joint, when disk 13 revolves.

In flanged opening 21 in bottom of box 16 and flanged opening 22 in plate 8 is placed

one open end of a curved pipe 23, reaching with its other open end inside of twyer 10, for purposes hereinafter explained.

Twyer 10 is of cylindrical design and provided in its outer walls with slots 24, placed around the circumference at a level corresponding to the inside of box 16. As these slots tend to separate the top part of the twyer from its lower end or at least to weaken this connection, one or more partitions 25 reaching higher up and lower down than the slots, strengthen the connection between the upper and lower parts of the twyer. At the same time they divide the slot region into compartments of which one compartment is made large enough to permit the curved pipe 23 to enter the twyer from the outside with enough clearance to allow of a certain amount of rotating movement to the twyer, without the pipe interfering. Spur gear 12 is acted upon by another gear 26 mounted on a vertical shaft 27, carrying lower down a pinion 28, acted upon by a rack 29. This rack itself receives its motion, through a connecting rod 30, a crank 31, mounted on a worm gear 32 acted upon by a worm 33 mounted on a shaft having another worm gear 34, that itself receives its motion through a worm 35 directly mounted on the shaft of a motor 36. The mechanical power arrangement thus described has for purpose to impart a slow alternating rotating movement to the twyer, over only part of the circumference. As the manner by which this particular rotating movement of the twyer is obtained, is immaterial, I have purposely limited myself in Fig. III. to mainly a diagrammatical illustration of an arrangement of that kind 40 to show that easy means can be devised to produce the particular motion of the twyer. Other means could naturally be chosen.

The twyer itself in its lower part may have a smooth outside cylindrical surface, but I prefer giving it purposely projections on the surface so designed that when the twyer rotates in either direction, these projections will help to impart a downward push to the coal contained in the distillation chamber. Thus Fig. VI. shows in its cross-section two oppositely located cylindrical projecting surfaces *a*, *b* on the outside circumference; Fig. VII. a cross-section taken lower down shows these projections gradually narrowed down to *c*, *d*. It is evident that in whatever direction the rotation of the twyer takes place, either the two faces *a*, *c* help to push the coal down while the two faces *d*, *b* make room for other coal to come down or vice versa. The lower end of the twyer is preferably made of a separate water-cooled nozzle 37 receiving water through a pipe 38 and evacuating it through a pipe 39. Nozzle 37 is fastened to twyer 10 by any convenient means, such as bolts

40. The alternate rotations of the twyer are meant to prevent the coal from sticking to the nozzle of the twyer.

The combustion or gas producing chamber 3 stands on the ash pit 41 of the producer. This ashpit is inclosed in brickwork 42 inside shell 2. A gas collector 43 provided all around with suitable openings 44 in its underside and leading to a gas pipe 43^a, is placed under combustion chamber 75 wall above the ash pit and fastened to shells 1 and 2. An operating tunnel 45 inclosed in walls 45^a and open at both ends, stretches diametrically across the ashpit, which it divides into two halves connected above the 80 tunnel. In the top part of the ashpit and below the combustion chamber is located an annular grate 46, built of any suitable material. On this grate rests the solid producer content. Between its outer rim and 85 the producer wall above is left an open annular space, as a convenient and the most effective means to make fall into the ashpit below, ashes and clinkers pushed over the grate from the center of the combustion chamber toward its circumference. This grate is supported in any convenient manner. I use hollow C. I. supports 47 open to the outside and fastened to shell 2 and supports 48 fastened to walls 45^a. 95

The bottom of the ashpit has slopes 49 and 50, leading automatically all ashes toward evacuation openings 51 and 55, which discharge the ashes automatically when open. Opening 51 that may have a damper 52 is continued by a curved pipe 53 extending with its lower open end deep enough into the water contained in tank 54 to make normally a waterseal. When damper 52 is raised this opening discharges the ashes 100 automatically and continuously. Whenever it is found necessary to empty tank 54, damper 52 is closed momentarily and the work in the producer need not be stopped. With the use of openings 55, closed normally by door 56, a short stoppage of the producer might be necessary, when opening door 56 for ash removing purposes. 110

Above the roof of the tunnel and extending from ash pit to lower part of combustion chamber, I place a metallic drum 57 forming so to say the hollow head of a downwardly directed stem or hollow cylinder or standpipe 58 that traverses a suitably finished opening in the roof of the tunnel 115 and is mainly located in the latter. This stem can slide over a hollow shaft 59, open on top and securely fastened below to a base 60. Cylinder 58 receives below a stuffing box 61. A smaller pipe 62, open on top and secured to base 60, extends upwardly inside pipe 59. The base 60 is so arranged that water can be admitted to standpipe 59 through pipe 63, to be discharged into drum, which it will leave through pipe 64 to be 130

led to any suitable place, preferably to the steam boiler, that furnishes the steam to be used with the hot air.

Drum 57, closed on top by a cover 65, has a lower cylindrical portion 66, surmounted by a crown 67 of an irregular elongated shape, not longer than the diameter of the cylindrical portion 66, but narrower in the other direction. The top of portion 66 reaches to or above the level of the highest point of the surrounding grate. Enough clearance is left between the drum and the surrounding grate, to allow the drum to revolve freely. A conical surface connects top of cylinder 66 to crown 67.

It can be seen that when revolving the drum, especially in the direction of the arrow, the peculiarly shaped crown will displace the ashes easily and push them toward the outside rim of the grate.

Cylinder 58 has a middle portion 58^a, somewhat reduced in diameter and provided with a key 68. On this portion is loosely mounted a worm gear 69, having an upper extension with a circular groove 70, into which groove engage loosely angle irons 71 fastened to lugs 72 on tunnel walls 45^a. The lower end 73 of stem 58 is again reduced in diameter so as to afford an offset that engages into the collar of lifting bar 74 suitably connected through its two ends with the tops of plungers 75, working in cylinders 76. These two cylinders are operated either by steam, compressed air or water under pressure admitted and evacuated through pipe 77. Gear 69 engages into a worm 78 mounted on shaft 79 running in journal boxes 80 suitably supported on brackets 81 on tunnel walls 45^a or otherwise. Shaft 79 has a bevel gear 82 at one end, engaging with another bevel 83 at the end of vertical shaft 84, which transmits the power imparted to gear 32 already mentioned. The power giving arrangement thus described may vary, as it is only employed as a means to obtain the desired results. The operating tunnel which may have any other shape and may be closed at one end, was adopted to lay within its confines the moving organs necessary to be placed on or near the drum stem, and thus not only remove them from the direct influence of the heat in the ashpit, but also to make their access easy at all times from the outside.

With the mechanical features above-described, the operation in the producer is carried out as follows:—Where the producer is lighted in the manner generally used in downdraft gas producers, which I do not reproduce here in order to avoid a too lengthy description, motor 36 is put in operation, whereby all automatic mechanical operations are started. Coal is regularly introduced through hoppers 9 into distillation chamber 6. The mixture of hot air and

steam arrives and enters through opening 20 and will have to fill up the whole air chamber 7 before it enters through air duct 19 and opening 18 into box 16 whence it enters twyer 10 through slots 24 to be discharged 70 lower through nozzle 37 into the combustion chamber 3 of the producer. The distillation chamber 6 being thus surrounded on all sides by hot air and steam, submits the raw coal to an energetic distillation; the 75 volatile products of the coal descend mainly directly from the distillation chamber to the combustion chamber below, while some of them will enter the curved pipe 23, to be discharged into nozzle 37.

The alternate partial rotation of the twyer makes it possible to prevent the descending coal or coke to stick to the bottom of the nozzle. The gases traversing the column of incandescent coke and ashes in the 85 combustion or gas producing chamber will leave the latter all around the circumference above the grate to enter the gas collector 43 and finally pipe 43^a. During the operation, gases, coke and ashes travel continuously all in the same downward direction, which naturally makes the ashes pack more or less in the lower part of the combustion chamber. The drum placed in the center of the grate has for purpose to overcome 90 this packing and to automatically evacuate the ashes. When admitting the motive power through pipe 77 into cylinders 76, plungers 75 raise drum 57 into dotted position 57^a, which movement will shake and lift up the material in the central part of the combustion chamber. When lowering it, the material will follow; the operation can be repeated until the central part of the column above is thoroughly shaken up and 100 loosened. The revolving motion, pushing the ashes from the center toward the outer rim of the grate, can go on undisturbed because cylinder 58 will slide through gear 69 without being interfered with by the rotating movement. The rotating drum has the advantage of always pushing the ashes from the center toward the outer rim of grate 46. Here the ashes will fall down and slide at once automatically to the discharge openings on either side. Drum 57 could also be used with a water-sealed gas producer. The drum may not be water-cooled in which case the water cooling appliances can be omitted. I have shown no 110 cleaning or poking doors in any part of the producer. Whether some are used or not, will in no way affect this invention.

The above description shows that the centrally located movable drum fills two main 120 purposes. Its revolving motions will have for effect to push the ashes and clinkers automatically from the center to the outside rim of the stationary surrounding grate, there to tumble automatically and continu- 130

ously into the ashpit below through the clear space left purposely between this outside rim and the producer wall above. To produce this effect it is necessary to give the crown above the level of the grate any shape that in its revolution will push the ashes as stated. Through this action, which I consider as novel, the drum fills the rôle of a centrally located ash removing apparatus. 10 Through its lifting motion, which I also consider as novel, it shakes and loosens the column of materials in the combustion or gas producing chamber above, breaks up the clinkers, and fills, therefore, the rôle of 15 a centrally located poker. These two functions, entirely independent of each other, can be filled by appliances different in design from the one illustrated.

The water being primarily introduced 20 into the drum for cooling purposes will naturally heat up to a certain extent before its evacuation. It is, therefore, of advantage to utilize the drum as a preheater of the water required to create the steam that it 25 is intended to mix with the hot air, introduced into the combustion or gas producing chamber. To obtain this result the water evacuation pipe 64 will form the feed pipe of the boiler, in which the above steam is 30 produced. These poking and ash removing appliances can be placed in other styles, such as, for instance, water-sealed gas producers.

What I claim is:—

35 1. In a gas producer, the combination with a gas producing chamber of an operating tunnel, a mechanically operated centrally located ashpushing and upwardly movable poking apparatus inside of said 40 chamber and above said tunnel, said apparatus having its immediate rotating means and independent lifting means located in said tunnel, substantially as described.

45 2. In a gas producer the combination with a gas producing chamber of an operating tunnel, a mechanically operated ashpushing and upwardly movable poking apparatus used as a water-preheater centrally located inside of said producer and having its immediate operating organs located inside 50 said tunnel, substantially as described.

55 3. In a gas producer the combination with a gas producing chamber of, an ashpushing and an upwardly movable poking apparatus centrally located in the lower part of said producer for work to be performed in said chamber, and below it mechanical means to revolve and mechanical means to lift said apparatus, said means working independently and without interfering with each other, substantially as described.

60 4. In a gas producer the combination with a gas producing chamber of an upwardly movable poking apparatus centrally located 65 in, and for the direct poking of, the lower

part of the ashbed in said chamber, and below it mechanical means to raise it independently of any revolving motion.

5. In a gas producer the combination with a gas producing chamber and an ashpit of, an operating tunnel separated by a partition from said pit, a revoluble and upwardly movable ashpushing and poking apparatus located centrally in the lower part of said producer above said tunnel for work to be 75 performed in said chamber, said apparatus having a stem extending downwardly into said tunnel, and in said tunnel mechanical means to revolve said stem, and mechanical means to lift it independently of its revolving motion, substantially as described. 80

6. In a gas producer the combination with a gas producing chamber and an ashpit of, an operating tunnel separated from said pit by a partition, an upwardly movable poking 85 apparatus provided with a hollow stem surrounding a standpipe, said stem extending downwardly into said tunnel, in said tunnel mechanical means to lift said stem, substantially as described. 90

7. In a gas producer the combination with a gas producing chamber, an ashpit and an independent annular grate with an annular opening between its outer rim and the surrounding wall of said producer for the purpose of evacuating ash from said grate into said pit, of an ashpushing and poking apparatus centrally located in the lower part of said producer for work to be performed above said grate, mechanical means to revolve and mechanical means to lift said apparatus, substantially as described. 95

8. In a gas producer the combination with a gas producing chamber, an ashpit having an ash discharge opening and a floor sloping toward said opening and an annular grate between said chamber and pit with an annular opening between its outside rim and the surrounding wall of said producer, of a centrally located ashpushing and poking apparatus inside of said producer for work to be performed above said grate, said apparatus being loosely surrounded by said grate, means to revolve and means to lift said apparatus, substantially as described. 100 105 110 115

9. In a gas producer the combination with a gas producing chamber, an ashpit having an ash discharge opening and a floor sloping toward said opening, between said chamber and said pit an annular grate leaving a free opening between its outer rim and the surrounding walls of said chamber, of a centrally located ashpushing apparatus in the lower part of said producer for the pushing of the ashes over said grate from 120 its central part toward its outer rim, said apparatus being loosely surrounded by said grate, below said apparatus mechanical means to revolve it, substantially as described. 125 130

10. In a gas producer the combination with a gas producing chamber, an ashpit, and a grate between said chamber and said pit of, an operating tunnel dividing said pit 5 into halves and separated from it by a partition, each of said halves having an ash discharge opening and a floor sloping toward said opening, said grate leaving an annular opening between its outer rim and 10 the surrounding wall of said producer, a centrally located ashpushing and upwardly movable poking apparatus loosely surrounded by said grate, in said tunnel mechanical means to revolve said apparatus, 15 and mechanical means to lift it independently of its revolving motion, substantially as described.

11. In a gas producer the combination with a gas-producing chamber of an ashpit, 20 an operating tunnel dividing said ashpit into two parts, a centrally located ash-push- 25 ing and mechanically operated poking apparatus, extending from said ashpit to said operating organs located in said tunnel, over 30 said ashpit an independent stationary grate loosely surrounding said ash-pushing apparatus and leaving an open space between said grate and the walls of said gas pro- 35 ducing chamber, an ash discharge opening in each of said parts of said ash-pit, each of said parts having a floor sloping toward its ash discharge opening, and mechanical means to operate said ashpushing and pok- 12. In a gas producer the combination

with a gas producing chamber of an ashpit, an operating tunnel dividing said ashpit into two parts, a centrally located ashpushing and poking apparatus extending from 40 said ashpit into said gas producing chamber with its immediate operating organs located in said tunnel, over said ashpit an independent grate loosely surrounding said apparatus and leaving an open space between 45 said grate and the walls of said gas producing chamber, an ash discharge opening in either part of said ashpit, each part of said ashpit having a floor sloping toward the ash discharge opening of said part, sub- 50 stantially as described.

13. In a gas producer the combination with a gas producing chamber of an operating tunnel, an upwardly movable, water pre- 55 heating poking apparatus, centrally located in the lower part of said producer, and in said tunnel mechanical means to operate said poker, substantially as described.

14. In a gas producer the combination with a gas producing chamber of, an operat- 60 ing tunnel, an ashpushing water preheating apparatus located in the lower part of said producer above said tunnel, and in said tunnel mechanical means to revolve said apparatus, substantially as described. 65

Signed at New York city in the county of New York and State of New York this 27th day of February A. D. 1912.
